(57) **CLAIM**

The ornamental design for a vehicle wheel face, substantially as shown and described.

DESCRIPTION

FIG. 1 shows a front view of a vehicle wheel face, showing our new design.

FIG. 2 is a side view thereof; and,

FIG. 3 is a perspective view thereof.

The rear portion of the vehicle wheel is shown in a lighter gray scale representing environmental subject matter that forms no part of the claimed design.

1 Claim, 3 Drawing Sheets

FIG. 1

FIG. 2

FIG. 3
